HIGHWAY CROSSING SIGNAL FOR
RAILWAYS

Harvey A. Haines, Philadelphia, Pa., assignor to
The Union Switch & Signal Company, Swiss-
vale, Pa., a corporation of Pennsylvania

Application June 12, 1936, Serial No. 84,836

13 Claims. (Cl. 246—130)

My invention relates to highway crossing signals for railways and particularly to means controlled by a train approaching the highway for delaying the operation of the signal according to the speed of the train, the delay varying inversely with the train speed.

The problem of controlling the operation of a highway signal at a railway crossing according to the speed of an approaching train so that the signal operates for substantially the same period for different train speeds has been the object of much inventive effort. Electro-mechanical means have been provided and intricate wiring systems have been suggested in the art. But there is still a need for a simple, reliable and positively operating device of this character, which can safely be depended upon. Obviously a wayside signal which occasionally fails is a greater menace than none at all.

Therefore one object of my invention is simplicity and the avoidance of less dependable mechanical elements. Another object is a positive operation of the signal which is not affected by a failure of the delay apparatus other than to increase the operating interval of the signal for slow trains. Still further objects and advantages of my invention will become apparent from the embodiments thereof which are described below with reference to the appended drawings.

Of the drawings, Fig. I shows diagrammatically an embodiment of my invention in which the delay feature is controlled by a track instrument actuated by the presence of a train.

Figs. II, III, IV, V and VI all relates to the embodiment of Fig. I, showing the different stages of operation of the device.

Fig. VII shows diagrammatically a second embodiment of my invention in which the track instrument is replaced by a relay control.

Fig. VIII shows diagrammatically a third embodiment of my invention in which the electrical wiring of the relay control of the delay feature (of Fig. II) has been simplified.

Fig. IX is a graph showing the relation between different train speeds and corresponding operating periods of the signal.

Fig. X is a graph showing the positions of trains running at different speeds in the track block of the system when the signal will be started in operation, and indicating in seconds the operating periods of the signal.

In Figs. I-VIII, 1 and 2 designates track rails of a railway; 3 a highway crossing and 4 a signal or other automatic device provided for the protection of traffic on the highway. In ac-

cordance with my invention, an operating block 5 of approximately 3300 feet in length is insulated at each end B and C by insulation 28 from the rest of the track, the highway crossing 3 being in said block 5 near the end C from which trains depart from the block 5. The entrance end of the block 5 is designated at B, a fixed point at which the presence of a train will positively start the operation of signal 4 unless delayed. A timing stretch 7 in advance of the block 5 is determined by a track instrument 6, positioned at point A, approximately 325 feet in advance of point B, which is the departure end of the timing stretch 7 as well as the entrance end of block 5. This track instrument may be any of the well known types now available. The lengths of the timing stretch 7 and of operating block 5 obviously may be varied and the timing of the contacts in selection relay 12 and in delay relays 18, 19 and 20 may be varied according to requirements, as will appear from the description below of the operation of the device.

The three embodiments will now be taken up separately and in order, beginning with that of Fig. I. For the purposes of this detailed description, the signal operating system proper will be to some extent separated from the delay apparatus, the former being described in detail first. The signal operating system is so designed that it is a complete operating unit whose operation is merely delayed by the delay apparatus which does not otherwise affect the signal operating system in case of a failure of the delay apparatus. This applies to the detailed description of all three embodiments.

The signal operating system is made up of a battery 8 connected to rails 1 and 2 of the block 5, a track relay 9 connected to block 5 in series with battery 8 and having a normally closed contact 11, a normally energized signal relay 24 controlled by contact 11 and having a normally open contact 25 which operates the signal 4 when closed and a battery 26 for operating signal 4. The signal relay 24 is of the slow releasing type, having a retardation in releasing of approximately one second after its control circuit is open. The shunting of track relay 9 by the presence of a train in block 5 thus positively operates signal 4 unless delayed.

To trace these circuits: The circuit controlling relay 9 in which battery 8 is connected with the rails 1 and 2 of block 5, is obvious from the drawings and needs no further attention. The presence of a train in block 5 shunts relay 9 and opens normally closed contact 11, closing

it again on departure from block 5, thus starting and stopping the operation of signal 4. The circuit controlled by contact 11, leads from contact 11 through wires 36 and 37 to signal relay 24, from relay 24 through wire 33 to battery 26 and back to contact 11 by wire 34. The normally open contact 25 operates the signal 4 when closed and the circuit leads from contact 25 through wire 38 to signal 4, by wire 33 to battery 26 which is connected to the other side of contact 25 by wire 34. It will thus be seen that the presence of a train on block 5 will open contact 11, which will close contact 25, operating signal 4; and the departure of the train from block 5 again closes contact 11, opening contact 25 which stops the operation of signal 4.

I now turn to the delay apparatus which is controlled in its operation according to the speed of an approaching train over timing stretch 7 and which may intervene in the operation of signal 4 to provide a delay period for slower trains. The operation of the delay apparatus is started by the track instrument 6 which is in a timing circuit including a battery 27 and selection relay 12. To trace this circuit: the track instrument 6 is connected to the battery 27 by wire 29 and to the selection relay 12 by wires 30, 31 and 32; the selection relay 12 is connected to the battery 27 by wire 33. The wire 30 includes a normally closed contact 10 opened by track relay 9 on deenergization to break this timing circuit when the train passes point B and enters block 5. Contact 13 operated by selection relay 12 has a quick make with a 90-second break period and its purpose is to open the timing circuit after the elapsing of a period greater than would be consumed by the passage of a slow train over the timing stretch 7 preparing for further operation of the device. This takes care of situations where a train stops on the timing stretch 7 or enters and then backs off it.

Because the track instrument 6 is but momentary in operation, contact 14 is interposed in the circuit 34, 35, 30, 31, 32, 33 and battery 26 to create a sustaining parallel circuit for relay 12 independent of battery 27. This sustaining circuit continues the operation of the selection relay 12 until the train enters the operating block 5 on leaving timing stretch 7. This track instrument 6 and the sustaining circuit could be replaced by a relay circuit connected to timing stretch 7 which should then be insulated like operating block 5. This modification would then energize relay 12 all during the period in which a train is present in timing stretch 7 without the need of a separate sustaining circuit. This modification is shown in Fig. VII, relay 47 with its associated circuits replacing track instrument 6 in Fig. I. Of course in cases where the track cannot be broken into a separate insulated timing stretch 7 because of other considerations, the device of Fig. I should be used. A further simplification of the device of Fig. VII is shown in Fig. VIII dispensing with line wires 51 and 50 of Fig. VII, described in detail below.

The selection relay 12, which is energized by the above circuits during the period occupied by a train in traversing the timing stretch 7, has three contacts 15, 16 and 17. These contacts 15, 16 and 17 are of the quick break type with delayed make periods of 4, 6 and 10 seconds respectively. These contacts 15, 16 and 17 control the energization of delay relays 18, 19 and 20 respectively. To trace these circuits: the battery 26 with wires 33 and 34 may be regarded as a com-

mon energizing circuit across which each relay 18, 19 and 20 is connected in series with its associated contacts 15, 16 and 17. Contact 15 is connected to relay 18 by wire 39, contact 16 to relay 19 by wire 41, and contact 17 to relay 20 by wire 43. The current thus flows from battery 26, over wire 34, through wires 39, 41 and 43 when contacts 15, 16 and 17 are closed, energizing coils of relays 18, 19 and 20 respectively, then through wire 33 and back to battery 26. When the relay 12 is energized, the contacts 15, 16 and 17 make one after another according to their delay intervals, energizing their respective delay relays 18, 19 and 20 in the same order until the train leaves the timing stretch 7 when those of contacts 15, 16 and 17 which were closed are again opened.

These delay relays 18, 19 and 20 have contacts 21, 22 and 23 respectively. These contacts are open when the relay coils are de-energized. They remain open when the relay coils are energized and then on the de-energization of the coils contact 21 closes for 15 seconds, contact 22 closes for 35 seconds and contact 23 closes for 80 seconds. This action requires that the relays must return to their de-energized position for the delay periods to function thereby insuring positive operation of the contacts in the delay relays.

These delay relays and selection relay 12 with contacts 13, 14, 15, 16 and 17 may be of the mercury contact plunger type, shown in U. S. Patent Nos. 1,967,247; 1,967,942; 1,967,944; 1,967,946; 1,967,947; 1,967,949; and 1,967,950 all granted to Carl H. Larson. The other relays may be of the type usually provided in railway signal systems.

The contacts 21, 22 and 23 are connected in parallel with each other and in series with battery 26 and relay 24 so that the closure of any contacts 21, 22 and 23 will keep signal relay 24 energized and thus delay the operation of signal 4 until all of the contacts 21, 22 and 23 are open. These contacts are also in parallel with contact 11 which ordinarily starts signal 4 into operation by opening as the train enters block 5. To trace these circuits: current flows from battery 26 over wire 34 to contacts 21, 22, 23 and 11, through wires 40, 36 and 37, through relay 24 to wire 33 and back to battery 26. It is clear that the operation of signal 4 would be controlled completely by contact 11 unless contact 11 be shunted by the closing of any of contacts 21, 22 or 23. Thus the delay in the opening of contacts 21, 22 and 23 determines the delay in the operation of the signal 4. In the case of a fast train, one doing better than 56 M. P. H., contacts 15, 16 and 17 do not have time to make during the period the train takes to traverse the timing stretch 7 and consequently the delay relays 18, 19 and 20 never operate, the signal 4 starting its undelayed operation at once as the train passes point B. If the train takes more than 4 seconds to traverse the timing stretch 7 and less than 6 seconds, only contact 15 has time to close and energize the coil of delay relay 18. On passing point B, the train de-energizes relay 18 and contact 21 closes for 15 seconds delaying the operation of signal 4 for that period. The operation of contacts 16 and 17 and delay relays 19 and 20 is the same as that of contact 15 and delay relay 18, as will be explained more fully below.

The operation of the system shown in Figs. I-VI is as follows: Let it be assumed that a fast train T is travelling along the railway track 1, 2 in the direction indicated by the arrow in the

figures of the drawings. In entering the timing stretch 7 (Fig. II) the track instrument 6 will be momentarily actuated and the circuit in which it is interposed will be closed through the battery 21, with attendant energization of the selection relay 12 and instantaneous closing of the contact 14, and the establishment of the auxiliary circuit previously described to keep the relay 12 energized. Now if the train T is proceeding upwards of 56 m. p. h. the 325 ft. timing stretch will be traversed in less than four seconds so that none of the contacts 15, 16, 17 of the selection relay 12 will be closed when the train T enters the block 5. Immediately upon entry of the train T into the block 5 (Fig. III), the battery 8 will be short circuited and the track relay 9 de-energized, allowing the contacts 10 and 11 to simultaneously open instantly with resultant de-energization of the signal relay 24 and closing 20 of the contact 25 to complete the circuit through the battery 26 and the signal 4 which thus starts operating immediately and remains in operation while the train T is traversing the 3300 feet of the block 5. During this time the contact 13 (which has a break period of 90 seconds) will obviously remain closed. The condition of the system during the entire time that the train T is travelling through the block 5 to the crossing 3 is as shown in Fig. III. Immediately upon the 30 passing of the train T beyond the highway 3, the system will reassure the normal condition shown in Fig. I as a consequence of the re-establishment of the circuit through the relays 9 and 24, with attendant closing of the contacts 10 and 11 and opening of the contact 25.

A slower train T passing into the timing stretch 7 and running between 37 and 56 miles per hour, will, as before, cause momentary actuation of the track instrument 6 and closure of the circuit through the battery 27 and the selection relay 12 with resultant closing of contact 14 as shown in Figs. II and IV. Also as before, the relay 12 will be kept energized through establishment of the circuit through the contact 14 and the battery 26. In this case, however, at the end of four seconds, the train T will have traveled less than the 325 feet of the timing stretch 7. Thus the contact 15 (having a four second delay) will be closed before the train T enters the block 5 (Fig. IV), as a consequence of which the circuit through the relay 18 and the battery 26 will be established, permitting contact 21 to close as soon as train enters block 5 which opens contact 15 of selection relay 12, de-energizing relay 18. The closing of contact 21 establishes a circuit through relay 24, so that the latter is kept energized to hold the contact 25 open notwithstanding short circuiting of the relay 9 and opening of the contacts 10 and 11 as the train T enters the block as shown in Fig. V. Opening of the contact 10 as shown in Fig. V does, however, result in the de-energization of the relay 12 and opening of the contact 15 to de-energize delay relay 18. Finally, the contact 21 (which has a delay period of fifteen seconds) opens when the train has traveled 380 feet in the block 5, assuming a hypothetical speed of 40 M. P. H., to the position shown in Fig. VI with resultant de-energization of the relay 24 and closing of the contact 25 to establish the circuit through the battery 26 and the signal 4 which, under these conditions, will operate for 41 seconds while the train is traversing the remaining length of the block 5.

Under the control of the contacts 16 and 17,

the relays 19 and 20 actuate the contacts 22 and 23 in a manner similar to that just described in connection with contact 15 and relay 18 in determining operating periods between 25 and 67 seconds and between 22 and 70 seconds of the signal 4 for train speeds respectively between 22 and 37 and between 15 and 22 miles per hour as indicated on the diagram in Fig. IX. The four curves of the graph in Fig. IX show at a glance, the operating periods of the signal for the four speed ranges for which the illustrated system is designated, the train speeds (M. P. H.) being indicated horizontally and the time (in seconds) being indicated vertically. The curve to the right shows the undelayed operation of the signal 4 under control of contact 11; the other curves from right to left show the delayed operation under control of contacts 21, 22 and 23 respectively.

I now turn to a consideration of the two modifications of the device of Fig. I as shown in Figs. VII and VIII, taking up Fig. VII first. The device in Fig. VII is quite similar to that described above in Fig. I, except that instead of the track instrument 6 with its associated circuit in Fig. I, there is substituted a relay 47 connected in series with a battery 46 through the rails 1 and 2 of timing section 7 which is insulated as indicated at 28 from the rest of the track at points A and B. This relay 47 operates contacts 48 and 49 in a circuit formed by wires 50 and 51 by which selection relay 12 is connected in series with battery 27. Wire 51 includes normally closed contacts 53 and 10. Contact 53 introduces an additional step in the functioning of contact 13 alone in Fig. I, the purpose in this case being to cut out the operation of the above mentioned circuit controlled by contacts 48 and 49 if relay 47 should fail to energize and open contacts 48 and 49. This cut out would then allow the signal 4 to operate without the delay apparatus until repairs were made or the device reset.

If relay 12 is not de-energized within 90 seconds, the contact 13 will open, it being of the slow break type. Contact 13 controls stick relay 52 which is energized by battery 26 with which it is connected in series by wires 33 and 34. Relay 52 operates contacts 53, 54 and 55 which are normally in the closed position. Contact 53 controls the timing circuit associated with relay 47; stick contact 54 controls relay 52; and contact 55 controls the operation of the delay contacts 21, 22 and 23. When relay 52 is de-energized all of the contacts 53, 54 and 55 fall open and the entire delay phase of the device is cut out of operation. It will thus be seen that contact 13 will not open unless relay 12 is energized for a period of 90 seconds after a train has entered the timing stretch 7. Normally the relay 47 becomes re-energized when the train leaves timing stretch 7, and opens the circuit energizing relay 12, in an interval of time less than 90 seconds. If a train T stops on timing stretch 7 and thus causes relay 52 to be de-energized before the train enters the block 5, the relay 52 will be automatically reset for the next train as the block 5 is entered by the first train proceeding, the signal 4 being operated without delay for the first train. This resetting is accomplished by a resetting contact 57 in wire 56 which shunts contact 13 and stick contact 54 in wire 34. This contact 57 is operated by relay 9 by the presence of a train in block 5. But if for some reason the relay 12 is energized for more than 90 seconds the delay phase will again be completely

cut out by the de-energization of relay 52 under control of contact 13.

The above description will be clarified by the following description of the operation of the

- 5 device. When a train T enters the timing section 7, relay 47 is shunted and contacts 48 and 49 are closed. This energizes selection relay 12 which operates exactly as described with reference to Fig. I above. To trace this piloting circuit: 10 the current flows from battery 27 through wire 50 including contact 49, relay 12, and wire 51 including contacts 10, 53 and 48, back to battery 27. As the train T enters block 5, relay 9 is shunted and de-energized, thus opening contact 15 10 which de-energizes relay 12 determining the selection of the delay relays 18, 19 and 20 as explained above in connection with Fig. I. The de-energization of relay 9, also closes contact 57 which has no effect unless either of contacts 54 20 or 13 were open. But if the train had stopped in timing stretch 7, relay 12 would then have continued in its energized state for 90 seconds when contact 13 would have opened, de-energizing relay 52 and cutting out the delay phase of the 25 device. In this situation contact 57 is effective in resetting relay 52 for as the train proceeds to enter block 5, relay 9 is de-energized which closes contact 57 re-energizing stick relay 52 and resetting the delay phase for the following trains. 30 However, if for some reason, relay 47 does not become re-energized the delay phase will continue in operation even after the train T leaves block 5. This is also prevented by contact 13 which will again completely cut out the delay 35 phase after the relay 12 has been energized for 90 seconds after the train leaves the block 5. The delay phase will not stay set unless functioning properly.

The device shown in Fig. VIII is similar to that of Fig. VII except that the timing circuit is made effective without the use of line wires 50 and 51 between the timing stretch 7 and the apparatus at the crossing 3. This is accomplished by the use of a polarized track relay 70 which corresponds substantially in function to relay 9 in Figs. I and VII. The reversal of current in rails 1 and 2 to which relay 70 is connected is accomplished by a reversal circuit of a usual type composed of wires 61, 62, 63 and 64, contacts 48, 49, battery 71, and relay 47 operating contacts 48 and 49 by the presence of a train on timing stretch 7. The reversal of current by the operation of relay 47 through relay 70 opens and closes contact 12, energizing and de-energizing relay 12 from battery 26 according to the presence or absence of a train T in timing stretch 7. Relay 12 is connected in series with battery 26 by wires 74 and 75, wire 74 including contacts 72, 10 and 53. It is obvious that the operation is the same as the arrangement of Fig. I except that relay 12 is controlled by relay 70 by a reversal of current instead of the track instrument 6 with its associated circuit in Fig. I or relay 47 with its associated circuit in Fig. VII.

65 The operation is as follows: As a train enters timing stretch 7, relay 47 is de-energized allowing contacts 48 and 49 to drop and reverse the flow of current through rails 1 and 2 of block 5 and through relay 70. This reversal of current closes contact 72, energizing relay 12, which operates as in Figs. I and II. As the train enters block 5 on leaving timing stretch 7, the relay 70 is shunted and contact 10 is opened, de-energizing relay 12 with the same effect as in Figs. I and VII. It is 70 to be noted that during reversal of current that

the contacts 57, 10 and 11 are momentarily opened and closed without disturbing their usual operation, relay 24 having a slow break period to bridge the interval.

If, however, the train delays its progress in timing stretch 7 for a period of more than 90 seconds, contact 13 of relay 12 will open and de-energize relay 52. Contact 53 of relay 52 then opens to de-energize relay 12. When the train proceeds, the signal 4 will operate during the entire time the train occupies block 5, since shunting of relay 70 opens contact 11. The train in block 5 also closes contact 57 which resets stick relay 52 cutting in the delay phase again. But if for some reason relay 12 is improperly energized when the train T leaves block 5, the delay phase will again be cut out after a period of 90 seconds. The delay phase will not stay cut in unless it is operating properly. Hence the signal 4 is assured a positive operation, either with a delay period or without one. The simplicity and efficiency of these arrangements for the practice of my invention are obvious and the feature of positive operation of the signal either with or without delay greatly advances the public safety at grade crossings. The economy inherent in an arrangement of this type is not the least of its advantages.

While I have described the embodiments of my invention in detail, it is obvious to one skilled in the art that many variations may be made and such variations do not involve a departure from the spirit of my invention as hereinafter claimed.

Having thus described my invention, I claim:

1. In combination, a stretch of railway track intersected by a highway, a highway crossing signal located at the intersection, initiating means for positively starting the operation of said signal as a train reaches a fixed point in advance of said crossing, an electrical delaying means for delaying the positive operation of said signal after a train passes said fixed point, said delaying means having a plurality of delay relays whose normally open contacts open after predetermined delay periods from de-energization of said delaying means, and electrical selection means for selecting, according to the speed of an approaching train, the delay relay to govern the delay period during which the signal shall not operate.

2. The invention of claim 1 characterized by the further fact that said selection means comprises a timing stretch of track in advance of said fixed point, a selection relay operated by the entrance of a train into said timing stretch, said selection relay having a plurality of delayed closing contacts of different closing periods controlling said delay relays, said contacts being connected to the delay relays in order beginning with the shortest delay period contact and the shortest delay relay, and a timing relay operated by the passing of a train over said fixed point from the timing stretch for de-energizing the selection relay and thereby selecting the delay relay last energized to govern the delay period before the signal begins to operate.

3. In combination, a stretch of railway track intersected by a highway crossing, a highway crossing signal located at the intersection, an insulated operating block in said track extending from a point in advance of said crossing to a point beyond the crossing, a timing stretch in advance of said first point and adjacent thereto, an operating relay for operating said signal during the presence of a train in said operating section, a selection relay energized by the entrance

of a train into the timing stretch and de-energized by the entrance of the train into the operating block on leaving the timing stretch, said selection relay having a plurality of delayed action contacts, and a plurality of delay relays governing the length of the period during which the signal's operation will be delayed, said delayed action contacts being connected in the ascending order of their delay periods to the delay relays in the ascending order of the delay periods of the latter.

4. In combination, a stretch of railway track intersected by a highway, a highway crossing signal located at the intersection, an insulated operating section in said track extending from a point in advance of the crossing to a point therebeyond, a timing stretch in advance of said first point and adjacent thereto, a normally energized operating relay which is de-energized by the presence of a train in said operating section, a normally energized signal which operates the signal when de-energized, said operating relay controlling said signal relay to operate the signal when a train is in the operating section, a selection relay having a plurality of delayed action contacts operated by the presence of a train in said timing stretch, and delay relays operated by said delay action contacts, each of said delay relays being connected to said signal relay to continue it in the energized condition thereby preventing the sounding of the signal until all of the delay relay contacts open.

5. The invention of claim 3 characterized further by the facts that said timing stretch is insulated from the adjacent track, that a relay is connected to said stretch to control the energization of said selection relay and that a delayed break contact operated by said selection relay cuts out the operation of said delayed action contacts after the selection relay has been energized for a predetermined period and deenergizes said selection relay.

6. The invention of claim 3 characterized further by the facts that said timing stretch is insulated from the adjacent track, that a relay is connected to said stretch to control the energization of said selection relay, that a stick relay cuts out the operation of said delayed action contacts after the selection relay has been energized for a predetermined period and deenergizes said selection relay, and that a contact operable by the presence of a train in said operating section resets said stick relay.

7. In combination a stretch of railway track intersected by a highway crossing, a highway crossing signal located at the intersection, an insulated operating block, an insulated timing stretch in advance of said block, electrical delaying means for delaying the operation of said signal according to the speed of a train in traversing the timing stretch, a relay means connected to said timing stretch for controlling said delaying means, an electrical cut out means for completely disconnecting said delaying means after a predetermined period of operation, and an electrical means for re-setting said delaying means.

8. In combination, a stretch of railway track intersected by a highway, a highway crossing signal located at the intersection, an insulating operating block extending from a point in advance of said crossing to a point in the vicinity thereof, a timing stretch in advance of said block, electrical means operating the signal during the presence of a train in said block, an electrical delaying means for delaying the operation

of said signal according to the speed of a train over said timing stretch, said delaying means being controlled electrically by a polarized relay controlled in turn by a current reversing circuit operated by a relay connected to said timing stretch.

9. The invention of claim 8 characterized further by the fact that said polarized relay is connected to said current reversing circuit through the rails of said operating block and said reversing circuit is operated by a relay connected to said timing stretch in series with a source of power so that the presence of a train shunts said power source.

10. In combination, a stretch of railway track intersected by a highway, a highway crossing signal device located at the intersection, initiating means for starting the operation of said signal as a train reaches a fixed point in advance of said crossing, electrical delaying means for delaying the operation of said signal after a train passes said fixed point, said delaying means being of the delay relay type and operating to delay the operation of said signal only if energized whereby a failure of the delaying means will not affect the operation of the signal, and automatic cut off means for terminating the operation of the delaying means at the end of a predetermined period and restoring the delaying means to its normal condition for future operation.

11. In combination, a stretch of railway track intersected by a highway, a highway crossing signal device located at the intersection, initiating means for starting the operation of said signal as a train reaches a fixed point in advance of said crossing, electrical delaying means for delaying the operation of said signal after a train passes said fixed point, said delaying means being of the delay relay type and operating to delay the operation of said signal only if energized and then deenergized, and an automatic cut off means which terminates the operation of the delaying means at the end of a predetermined period restores the delaying means to its normal condition for future operation.

12. In combination, a stretch of railway track intersected by a highway, a highway crossing signal device located at the intersection, initiating means for starting the operation of said signal as a train reaches a fixed point in advance of said crossing, electrical delaying means for delaying the operation of said signal after the train passes said fixed point, said delaying means being of the delay relay type and operating to delay the operation of the signal only if energized and then deenergized, and an electrical selection means which determines the period of operation of said delaying means according to the speed of the train approaching said fixed point.

13. In combination, a stretch of railway track intersected by a highway, a highway crossing signal device located at the intersection, initiating means for positively starting the operation of said signal as a train reaches a fixed point in advance of said crossing, electrical delaying means for delaying the positive operation of said signal after a train passes said fixed point, said delaying means having a plurality of delay relays whose normally open contacts open after predetermined delay periods from deenergization of said delaying means, electrical selection means for selecting according to the speed of an approaching train the delay relay to govern the delay period during which the signal shall not operate; said selection means comprising a timing stretch of track in

advance of said fixed point and a selection relay operated by the entrance of a train into said timing stretch and having a plurality of delayed closing contacts of different closing periods for 5 selectively controlling said delay relays with said contacts connected to the delay relays in order beginning with the shortest delay period contact and the shortest delay relay; a timing relay operated by the passing of a train over said fixed 10 point from the timing stretch for deenergizing

the selection relay to select the delay relay last energized to govern the delay period before the signal begins to operate, and means including a cut off contact operative to interrupt the operation of the selection relay after a predetermined period and to at once restore said delaying means to its normal condition in preparation for further operation. 5
